WINDING MACHINE.

Application filed August 27, 1927. Serial No. 215,803.

This invention relates to machines for winding yarn into packages in which the windings are traversed around a single axis. The principal object is to provide a simple mechanism requiring no special skill in its control and operation whereby compact and stable packages of the stated kind can be formed.

In the drawings,

10 Fig. 1 is a side elevation of one complete winding unit;

Fig. 2 is a front elevation of the upper part of such unit; and

Fig. 3 is a plan.

15 Supporting means is in part afforded by a fixed frame structure 1 in which may be suitably journaled on a horizontal axis a drive wheel 2 constantly rotated. Another part of such supporting means is a forked 20 upstanding carrier 3 fulcrumed on a shaft 4 which is fixed by a set-screw 5 in the forwardly projecting ends of a bifurcated bracket 6 projecting from and in effect forming a part of frame 1, said carrier having 25 journaled therein the shaft 7 of the yarn traverser which comprises with said shaft the cylindrical hollow traverser proper or drum 8, formed as two counterpart parts with an intervening sinuous space or slot 9, 30 and a wheel 10, said parts of the traverser and the wheel being all fixed on the shaft. On the tilting of the carrier one way the traverser, by its wheel 10, encounters the wheel 2 so as to be rotated thereby, and on 35 tilting thereof the other way the carrier, also by said wheel, encounters a brake member 11 projecting from and fixed on shaft 4. The brake member 11 has an arm 11^a projecting under an arm of bracket 6 and 40 provided with a set screw 11^b taking against the latter to permit adjustment of said member to be effected toward and from the wheel.

45 The carrier 3 serves in the example to maintain the core of and hence the package being wound above the drum as well as a support for the traverser, the upper ends of its fork extremities being themselves forked or formed with upwardly open crotches or 50 guideways 12 affording bearings for the ends

of the spindle 13 of the core 14, the latter taking between said extremities and so being confined against endwise movement. The core (and the package 15 while being formed) has frictional contact with and so is rotated by the rotated drum of the traverser, being preferably held under some pressure against the latter by a gravity-actuated forked presser or follower 16 fulcrumed on a rock-shaft 17 journaled in a bracket 18 projecting from and in effect forming a part of frame 1, the ends of the follower arms then bearing on the ends of spindle 13; such follower may be shifted to the dotted-line or idle portion in Fig. 1. 60 Shaft 17 in effect forms part of a lever structure which controls the shifting of carrier 3 to move the traverser from one to the other of the parts 2 and 11 and also the shifting of the follower into and out of its 65 working position (full lines, Fig. 1), thus: on the shaft 17 are fixed an overlying forwardly extending arm or handle 19 and an eccentric 20, the handle having a lug or toe 19^a projecting forward under a suitable 70 abutment 16^a of the follower; and embracing the eccentric is an eccentric strap 21^a formed on one end of a link 21 which passes freely through an arm of the carrier and has a nut 22 screwed on its free end and a spring 75 23 coiled about it and interposed between 80 said carrier arm and a shoulder 21^b.

The means to deliver the yarn to be wound in accordance with this invention is arranged beyond the drum with reference to the core, 85 What form it takes is not especially material, but in the example it comprises the supply, represented as a short section of tubing 23 having the yarn wound thereon at 24 and hung loosely and so as to shift relatively on a stud 25 projecting from the frame, tension means 26, and a guide 27 between the tension means and drum.

When the handle 19 is elevated (dotted-line position) the presser 16 is held elevated 95 by lug 19^a, so that the crotches 12 are cleared for removal of a full package and introduction of an empty core; and the carrier stands shifted to the left, under pressure of the springs, so that the traverser wheel 10 100

is against the brake-member 11 and the traverser at standstill, spring 23 being compressed. An empty core is placed in the crotches with a few turns of the yarn A 5 hand-wound thereon, and the handle lowered, resulting in presser 16 bearing down on the core and in carrier 3 being shifted to bring the traverser wheel against the rotating wheel 2; it is desirable that the 10 rotating of the traverser and hence of the core should not start until the core is gripped between the presser and traverser, so the stated shifting of the carrier is delayed to occur until after the presser is seated on the core 15 by setting back nut 22 so that it does not cause such shifting until the presser is so seated. The winding now proceeds with a traverser, as will appear, and when the package has been wound to some predetermined 20 extent the attendant raises the handle, resulting in the traverser and the package being brought to a standstill and then the presser elevated so that the package can be removed from the crotches. The normal 25 position of the handle is down, its weight as well as that of the presser then acting to hold the package in good frictional contact with the traverser.

The slotted traverser is both the means to 30 rotate the core by frictional contact therewith and the means for traversing the thread which, as shown in Fig. 1, extends through slot 9 from the yarn delivery means at one side of the traverser to the core at the 35 opposite side. It is not new to use a sinusously slotted traverser for traversing the yarn (by engagement of the yarn in the slot) with respect to the core while the winding is proceeding. But, so far as I am 40 aware, it is new to cause the core, held bearing against such a traverser, to be driven frictionally by the traverser. As the yarn sweeps back and forth in traversing its point of incidence with the package lags 45 behind the particular point at which it is issuing from the slot, as indicated by line a—b in Fig. 2 where the traverse then occurring is assumed to be to the right. The degree of this lag or obliquity (with respect 50 to the axis of either the core or traverser) increases as the package grows, because the distance between the point of issuance of the yarn from the traverser slot to the point of its incidence with the package (as viewed 55 in side elevation, Fig. 1) increases as the package grows; and this results in the desirable advantage that since the effective traverses reduce in length as the package builds up the latter is formed with conical 60 ends. The cone formed at each end will be moreover appreciable, to the end that the stability of the package will be greatly increased, if the yarn delivery means is remote from rather than close to the line of 65 contact between the traverser and package,

as where in the example such means is beyond the traverser relatively to the package.

Having thus fully described my invention, what I claim is:

1. In combination, supporting means, a substantially cylindrical yarn traverser revoluble therein and having a sinuous yarn-traversing and receiving slot formed therein around said axis, said supporting means having guideways extending in lines crossing the periphery of the traverser and forming bearings, a freely revoluble core for the yarn windings removably arranged in said guideways, a presser normally holding the core in peripheral friction-driven contact with the traverser and movable in said means to permit removal of the core from the guideways, and yarn delivery means from which the yarn extends through said slot to and around the core. 75

2. In combination, supporting means, a constantly rotated driving member therein, a brake opposite the periphery of said member, a part of said means being a carrier movable between and toward and from said brake and member, a revoluble driven member journaled in the carrier and movable therewith in one direction against the driving member and in the other against the brake, and a core for the windings held in peripheral friction-driven contact with the driven member and revoluble in said means. 90

3. In combination, supporting means, a constantly rotated driving member therein, a brake opposite the periphery of said member, a part of said means being a carrier movable between and toward and from said brake and member, a revoluble driven member journaled in the carrier and movable therewith in one direction against the driving member and in the other against the brake, a core for the windings held in peripheral friction-driven contact with the traverser and revoluble in said means, and means normally urging said carrier in one direction in which it is movable and movable to shift the carrier in the opposite direction. 100

4. In combination, supporting means, a constantly rotated driving member therein, a brake opposite the periphery of said member, a part of said means being a carrier movable between and toward and from said brake and member, a revoluble driven member journaled in the carrier and movable therewith in one direction against the driving member and in the other against the brake, a core for the windings held in peripheral friction-driven contact with the driven member and revoluble in said means, and means normally yieldingly urging said carrier in one direction in which it is movable and movable to shift the carrier in the opposite direction. 115

5. In combination, a fixed supporting 130

structure, a constantly rotating driving member journaled therein, a driven member, back-and-forth movable means arranged in said structure and in which said driven member is journaled and by which it is adapted to be moved into and out of friction-driven engagement with the driving member, said means having guideways crossing the periphery of the driven member, a core for the yarn windings journaled in the guideways, and a presser movably arranged in said structure for holding the core against the driven member, said presser being adapted to be retracted from the core by said means on moving the latter to retract the driven member from the driving member.

6. In combination, a fixed supporting structure, a constantly rotating driving member journaled therein, a driven member, back-and-forth movable means arranged in said structure and in which said driven member is journaled and by which it is adapted to be moved into and out of friction-driven engagement with the driving member, said means having guideways crossing the periphery of the driven member, a core for the yarn windings journaled in the guideways, and a presser movably arranged in said structure and holding the core against the driven member, said means in its movement to withdraw the driven member from the driving member being adapted to retract the presser from the core after the driven member clears the driving member.

In testimony whereof I affix my signature.
CHARLES C. JESSEN.
